CLEANING DEVICE

William Joseph Turpin, Santa Ana, Calif.

Application May 21, 1937, Serial No. 144,189

2 Claims. (Cl. 141—1)

This invention relates to improvements in cleaning devices and has particular reference to a device for cleaning meters, such as gas meters, which become coated with sediment, tar, oil and other greases which interfere with their proper functioning.

A further object is to produce a device of this character wherein a meter of any size may be cleaned thoroughly, economically, and without introducing any hazard to the operator.

A further object is to produce a device of this character which may be readily placed in any location where such work is to be done.

Other objects and advantages will be apparent during the course of the following description.

In the accompanying drawings forming a part of this specification and in which like numerals are employed to designate like parts throughout the same,

20 Fig. 1 is a front elevation of my meter cleaning trough and tray;

Fig. 2 is a top plan view of Fig. 1;

Fig. 3 is an enlarged detailed cross sectional view taken on the line 3—3 of Fig. 2;

25 Fig. 4 is an enlarged fragmentary detailed view of one of the cleaning nozzles; and

Fig. 5 is a front elevation of a meter, showing the top and valve chamber cover removed.

The ordinary gas meter is so constructed that 30 it is necessary from time to time to clean the interior of the meter in order to remove sediment and other foreign matter, which interferes with the proper functioning of the meter. It is necessary to employ a solvent to dissolve the deposit 35 in the meter.

I have, therefore, devised an arrangement whereby a solvent is forcibly ejected into and through the meter, and then the meter is given a scrubbing operation, whereby all solvent employed is recovered.

In the accompanying drawings wherein for the purpose of illustration is shown a preferred embodiment of my invention, the numeral 5 designates a table in which is mounted a trough 6 45 and a tray 7. The tray 7 has a support 8 which is slotted so as to slidably hold a series of washer nozzles 9 and 11, and 12 and 13. These nozzles are connected by flexible pipes 14 to an air line

16. A circulating pump is shown at 17, having 50 a discharge pipe 18, emptying into the tray 7, and having an end 19 secured to a flexible hose 21 which may be used for sucking up any cleaning solvent which may have remained in the meter after the same has been cleaned. A brush 22 55 is rotated on a vertical spindle 23, which is driven

through a reduction gear by the motor 24. The nozzles 9 and 11 are adapted to engage inlet and outlet pipes of the meter; and one of these nozzles is shown in Fig. 4, where it will be noted that the jet 26 discharges into the nozzle; and as a result, the liquid A is forcibly driven by the stream of air from the nozzle and into the meter. The nozzles 12 and 13 are each provided with a cap 27, which effects a spray as the fluid issues from the nozzle.

10 In Fig. 5 I have shown a meter having the top and the valve chamber cover removed. Therefore, when the meter is turned upside down, as shown in dotted lines in Fig. 3, the nozzles 9 and 11 will engage the inlet and outlet pipes 15 of the meter, while the nozzle 12 will enter the valve chamber, and the nozzle 13 will enter the interior of the meter.

The operation of my device is as follows:

Assuming that the cover of the meter and the valve chamber have been unsoldered and removed, the meter is turned upside down, the air pressure turned on, and the solvent will then be forced upwardly through all of the nozzles into and through the meter, thus removing any 25 deposit which may have accumulated therein. The meter is now moved to the trough 6, the rotary brush 22 being rotated in the meter as the same is moved thereover. This brush tends to remove any further deposit which might be retained; and if the solvent has not entirely left the meter through its upside down draining action during the scrubbing and brushing operation, then the end 19 of the flexible hose 21 may be inserted in the meter; and as the pump 17 is 30 operating, any remaining solvent will be withdrawn. Also any solvent in the trough will be withdrawn and discharged into the tray.

35 It will thus be seen that I have produced a device which will clean meters most effectively.

40 It is to be understood that the form of my invention herewith shown and described is to be taken as a preferred example of the same and that various changes relative to the material, size, shape and arrangement of parts may be 45 resorted to without departing from the spirit of the invention or the scope of the subjoined claims.

Having thus described my invention, I claim:

50 1. In a device of the character described, comprising a tray element adapted to retain a solvent solution, a horizontal support arranged in said tray element below its upper end and having a slot therein, a plurality of nozzles horizontally adjustable in said slot independent of each other,

a compressed air line connected to said nozzles within the solution in the tray element, whereby the solvent solution will be forced out through said nozzles by said compressed air.

5. 2. In a device of the character described, comprising a tray element adapted to retain a solvent solution, a horizontal support arranged in said tray element below its upper end and having a slot therein, four nozzles horizontally adjustable

in said slot independent of each other, the two outside nozzles terminating below the upper end of the tray element, and the two inside nozzles terminating above the tray element, and a compressed air line connected to the said nozzles within the solution in the tray element, whereby the solvent solution will be forced out through said nozzles by said compressed air. 5

WILLIAM JOSEPH TURPIN.
